US0D1014458S

(12) **United States Design Patent** (10) **Patent No.:** **US D1,014,458 S**
(45) **Date of Patent:** **** Feb. 13, 2024**

(54) **HEADPHONES**

(71) Applicant: **SHENZHEN SHOKZ CO., LTD.**,
Guangdong (CN)

(72) Inventors: **Lei Zhong**, Shenzhen (CN); **Zhi Cai**,
Shenzhen (CN); **Sunjie Huang**,
Shenzhen (CN); **Zeteng Yan**, Shenzhen
(CN); **Qian Chen**, Shenzhen (CN);
Piyou Cheng, Shenzhen (CN);
Yueqiang Wang, Shenzhen (CN)

(73) Assignee: **SHENZHEN SHOKZ CO., LTD.**,
Shenzhen (CN)

(**) Term: **15 Years**

(21) Appl. No.: **29/792,745**

(22) Filed: **Apr. 21, 2022**

(30) **Foreign Application Priority Data**

Oct. 22, 2021 (CN) 202130694639.5

(51) LOC (14) Cl. **14-01**

(52) U.S. Cl.

USPC **D14/205**; D14/226

(58) **Field of Classification Search**

(57) **CLAIM**

The ornamental design for headphones, as shown and described.

DESCRIPTION

FIG. 1 is a right perspective view of headphones showing our new design;

FIG. 2 is a left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claimed design while all other broken lines depict portions of the headphones that form no part of the claimed design; all broken lines form no part of the claimed design.

1 Claim, 8 Drawing Sheets
